Primary Examiner — Elizabeth J Oswecki(74) *Attorney, Agent, or Firm* — Rosenberg, Klein & Lee(57) **CLAIM**

The ornamental design for a diffusion assembly for front opening unified pod, as shown and described.

DESCRIPTION

FIG. 1 is a perspective view of a diffusion assembly for front opening unified pod showing our new design;

FIG. 2 is a front view thereof;

FIG. 3 is a cross sectional view taken along line 3-3 of FIG. 2;

FIG. 4 is a cross sectional view taken along line 4-4 of FIG. 2;

FIG. 5 is a rear view thereof;

FIG. 6 is a right side view thereof;

FIG. 7 is a cross sectional view taken along line 7-7 of FIG. 6;

FIG. 8 is a left side view thereof;

FIG. 9 is a top plan view thereof; and,

FIG. 10 is a bottom plan view thereof.

The broken lines in the drawings illustrate the portions of the design that form no part of the claim.
